GYRATORY CRUSHER WITH POWER HEAD
ADJUSTMENT

Samuel W. Traylor, Jr., Allentown, Pa.

Application September 13, 1946; Serial No. 696,879

16 Claims. (Cl. 241—213)

1

This invention relates to gyratory crushers of the type having an upright shaft to which a gyratory movement is imparted by a rotary eccentric in which the shaft is journaled for free rotary movement caused by the rolling of a head, secured to the shaft, on the material between it and a concave. Such shafts are ordinarily axially slidable in the eccentric and are provided with an adjustable support at the upper or lower end of the shaft so that the shaft can be adjusted vertically for the purpose of positioning the head relative to the concave for a fine or coarse product, as the case may require. Ordinarily these shaft adjustments are accomplished manually and while they are being made the crusher has to be stopped. It is an object of the present invention to provide a power adjustment for the shaft in one or both directions, deriving the power for one adjustment from the rotary motion of the shaft during operation of the crusher and for the opposite adjustment, from its gyratory motion. It is a further object of the invention to provide an improved bottom support for the shaft. Illustrative embodiments of the invention are shown in the accompanying drawings in which

Figure 1 is an axial section of a crusher equipped for power adjustment of the shaft either up or down.

Figure 2 is a section substantially on line 2—2 of Figure 1.

Figure 3 is a section substantially on line 3—3 of Figure 1.

Figure 4 is a section of a modified form of apparatus in which the crusher shaft is adjustably supported from above, substantially on line 4—4 of Figure 5 of a crusher equipped for power adjustment of the shaft in one direction only, and

Figure 5 is an axial section of the upper portion of a crusher, the section being taken substantially on line 5—5 of Figure 4.

Referring to Figures 1 to 3, the crusher comprises a frame including an upper section 10 and a lower section 11. The lower section has a hub with a vertical bore 12 in which, through the intermediary of a bushing 13, is journaled a rotary member or eccentric, comprising a cylindrical portion 14 and a lower annular flange 15 supported on an anti-friction thrust bearing 16, a bevel gear 17 being fixed to flange 15. Reference numeral 18 designates a horizontal shaft journaled in a frame extension and having fixed on one end a pinion 19 in engagement with gear 17 and on the other a drive pulley 20.

2

The eccentric has an eccentric bore 21 whose axis is tilted relative to the axis of rotation of the eccentric, the bore terminating downwardly at an annular flange 22 whose top surface constitutes the bottom of the bore, is in a plane normal to the axis of the bore 21, the flange defining a circular opening 21'. Reference numeral 23 designates a nut having a top out-turned flange 24 by which it is supported on flange 22 through an anti-friction bearing 25, the nut being coaxial with the bore 21 and projecting freely downwardly through opening 21'. The nut engages a threaded supporting portion or plug 26.

Received in the bore 21 with freedom of rotation is a sleeve 27 which is supported by and coupled with nut 23 through a suitable coupling member 28 here shown as an Oldham's or double slider coupling. The interior of the sleeve is enlarged at its upper end so that a shoulder is provided on which is supported one portion 29 of a spherical socket assembly whose other portion 30 is held in place by a threaded ring 31, the socket assembly engaging a ball 32 provided with a diametrical bore which freely receives the lower cylindrical portion 33 of the crusher shaft 34. The lower end of the shaft is supported on and coupled with the supporting portion or plug 26 through an Oldham's coupling 35, as here shown. The nut 23, plug 26, and sleeve 27 which is coupled with the nut, constitute an upright cup-like bearing unit for the shaft 34, the plug constituting the bottom end wall of the cup and, as here shown, being vertically adjustable.

The upper end of casing section 11 is upwardly flared to a circular rim 36 whose inner and outer walls converge upwardly. The top section 10 includes a ring 37 having a bottom flange 38 channeled to mate with the rim 36. Ring 37 includes an inwardly projecting annular flange 39 having a downwardly flared inner edge, and above the flange 39 the ring includes a collar portion 40 which terminates upwardly in an out-turned flange 41. The ring is tiltably secured to the rim 36 by means of bolts 42 which pass through enlarged openings in the latter and in flange 38, the lower ends of the bolts being surrounded by compression springs 43 which abut upwardly against the bottom of rim 36 and downwardly against a sectionalized ring 44 so that ring 37 is yieldingly held against rim 36 with the possibility of tilting relative thereto, as permitted by the coupling 35, for the relief of stresses.

Seated against and supported by the inner edge

of flange 38 is the mating marginal portion of a concave 44, the concave having an outer face flaring downwardly, and engaged between this face and the inner face of collar portion 39 is a wedge ring 45 which, through a top flange 46, is bolted to flange 40 of ring 37 by means of bolts 47. Ring 45 is formed with a spider including arms as at 48 which support a bearing housing 49 into which the upper end of shaft 34 extends, the shaft end being supported by means of a ball and socket arrangement, like that at its lower end, for gyratory movement with capability of axial adjustment. Ring 37 also supports a feed hopper 50.

Secured on an upwardly tapering portion of shaft 34 by means of a nut 51 is a head 52 which, as here shown, includes a core 53 and a mantle 54, and in the space between the head and concave is disposed a crushing ring 55 which is a preferred feature but forming no part of the present invention, being claimed in my copending application, Serial No. 643,033, filed January 24, 1946 now Patent No. 2,498,774, Feb. 28, 1950.

As is well understood, when the eccentric is driven from pulley 20, the shaft 34 is given a gyratory motion. That is to say, its axis moves in a conical path whose apex is at the neutral point 56 of the shaft. Inasmuch as nut 23 is always coaxial with the shaft, it too will gyrate or planetate. Furthermore, since the supporting portion 35 is coupled to the shaft and since the friction between it and the nut is greater than that between the nut and its support, the nut will participate in the rotation of the shaft. How these movements of the shaft are taken advantage of to effect axial adjustment in either direction will now be described.

Keyed to the lower end of nut 23 are gears 60 and 61 having external teeth which, as here shown, Figures 2 and 3, are generally triangular. Surrounding gear 60 is an internally toothed orbit gear 62 which, through a spacer 63 is supported on an internally toothed orbit gear 64 which surrounds gear 61, gear 64 being supported on a shoulder provided by a cap member 65 which forms the bottom portion of frame section 11. Gears 62 and 64 have cylindrical outer peripheries and are rotatably received in a cylindrical cap portion 66 coaxial with the axis of rotation of the eccentric.

As shown in Figure 2, gears 60 and 62 have the same number of teeth and their size relation is such that gear 60 can planetate about the axis of gear 62 in engagement with the latter. If the gear 60 were not rotating, then its planetation would have no effect on gear 62. However, assuming the direction of shaft gyration to be counter-clockwise, then the crushing head, rolling on the material in the crushing space, will be rotated clockwise. As a specific example, assume the head to be 36" in diameter and to be set to one inch on the closed side, then the head would be rolling on a circle which is 37 inches in diameter and its distance of rotation during one complete gyration would be 3.1416 inches, and gear 62 would be rotated to the same extent clockwise.

Reference numeral 67 designates a vertical rock shaft journaled in the top and bottom walls of a pocket 68 off of the cylindrical portion of the cap 65, the lower end of the shaft projecting through a gland 69 and having secured thereto an arm 70. Fixed on the shaft in the horizontal plane of gear 62 is a dog 71 adapted to cooperate with notches 72 in the periphery of gear 62 to

arrest the rotation of the latter as shown in Figure 2. When this occurs, the rotation of nut 23 is also stopped, but since the shaft and the supporting member 26 continue to rotate, they will be moved up or down depending on the direction of the threads between the supporting member and the nut. Preferably, the threads are left hand so that when the nut is arrested, an upward adjustment will be effected. The dog and notches are so shaped that the latter exert an outward camming effect on the dog so that the latter has to be held to prevent being thrown out. Should it be held too long so that the shaft or head jams upwardly, the resultant jamming of the interengaged threads will cause the nut to be rotated and gear 62, being thus driven, will throw out the dog or at least warn the operator to release the handle.

Gear 64, on the other hand, has a greater number of teeth than gear 61, the ratio as here shown being 23-to-20. The size relationship of the gears is such that gear 61 can planetate about the axis of gear 64 in engagement with the latter. In view of this ratio, gear 64 will normally be driven counter-clockwise.

Fixed on shaft 67 in the horizontal plane of gear 64 is a dog 73 adapted to cooperate with notches 74 of gear 64 to arrest the latter as shown in Figure 3 and it will be noted that the relative disposition of dogs 71 and 73 is such that both are disengaged or one or the other is engaged with its associated gear. When the rotation of gear 64 is arrested, the result is that gear 61 will be driven clockwise a distance of 3 teeth for each gyration. This angular movement is substantially greater than 10°, which is assumed to be the normal angle of shaft rotation for each gyration, and, consequently, nut 23 is driven faster than member 26 so that the latter will be displaced in a direction opposite to that in which it was displaced when the nut was held stationary as in Figure 2.

When dog 73 is out of contact with the orbit gear 64, and with gear 61 gyrating in a counter-clockwise direction and rotating in a clockwise direction, approximately 10 degrees per gyration, gear 64 will rotate in a counter-clockwise direction a distance, in each gyration of the internal gear 61, equal to the difference between the amount of rotation of the internal gear in said gyration (10 degrees) and the planetary advance in said gyration (three teeth, or approximately 47 degrees), said difference being approximately 37 degrees.

As noted above, however, when rotation of gear 64 is arrested by dog 73, gear 61, during each gyration, will be advanced in a clockwise direction, a distance equal to three teeth or approximately 47 degrees and the nut 23 will be correspondingly advanced. Since the shaft and the threaded supporting member 26 rotate only approximately 10 degrees during each gyration, the nut is advanced substantially 37 degrees with respect thereto, thereby displacing the shaft relative to the supporting nut.

The gears 64 and 61, in combination with dog 73, constitute means for transmitting force from the gyratory motion of the shaft to the nut to rotate the same faster than the normal rotation of the shaft in the same direction as the shaft during each gyration thereof, thereby to adjust vertically the shaft with respect to the nut.

It will thus be evident that merely by the appropriate rocking of shaft 67, the crusher shaft

can be quickly moved either up or down while the crusher is in operation.

While in Figure 1 the gear ratio is 1 to 1, it will be evident that this ratio could be varied so long as the ultimate effect is to cause the nut to rotate more slowly than the main shaft. If gear 62 had more teeth than gear 60, then, the same as in Figure 3, the outer gear would normally be driven counter-clockwise so that dog 71 and the notches would have to be designed to prevent rotation in that direction.

In Figures 4 and 5, reference numeral 80 designates a spider-supported bearing housing into which projects the upper end of a gyratory shaft 81 whose lower end is journalled in an eccentric and is axially slideable therein as in common practice. The bearing housing supports a bushing 82 which surrounds the shaft and is bored on a taper to accommodate the motion of the shaft, and supported on an out-turned flange 83 of the bushing is a bronze ring 84 which has a spherical upper surface generated about the neutral point of the shaft. The threaded upper end of the shaft, which in this case constitutes the supporting portion, is engaged in a nut 85 which has a bottom spherical surface mating with the spherical surface of ring 84 and rotatable thereon. Formed on the upper end of the nut is a gear 86 which is gyratory within an internally toothed gear 87 rotatably supported in the upper part of the housing on the vertical axis of the crusher. At one side, the housing is enlarged to provide a pocket 88 through which extends a vertical rock shaft 89 whose lower end is accessible for manipulation, and within the pocket the shaft has fixed thereto dogs 90 and 91 in angular relation. Assuming that the direction of normal shaft rotation is clockwise, then, just as in Figure 2, gear 87 is normally driven clockwise. Its rotation can be arrested by swinging dog 90 into a notch 92 in the periphery of gear 87, and in that case, the rotating shaft will thread itself upwardly if provided with a left-hand thread as shown in Figure 5. The gyratory motion at the top of the shaft is not sufficient to enable it to be taken advantage of as in Figure 3. However, by swinging dog 91 into engagement with a notch 93 of gear 87, the nut can be held against rotation while the shaft is manually turned as by means of a bar inserted in notches as at 94 in the upper end of the head. With dogs 90 and 91 both in neutral position, nut 86 rotates with shaft 81 and carries gear 87 with it.

It will be understood that variations in the form and arrangement of parts other than those shown are possible and are contemplated under the invention as defined in the following claims.

I claim:

1. In a gyratory crusher comprising an upright shaft, a rotary member in which one end of said shaft is eccentrically journalled and is slideable, a head fixed on said shaft and a fixed concave surrounding the head, a nut rotatably supported at one end of said shaft, a supporting portion for the shaft threaded in said nut and rotating with the shaft and in turn normally rotating said nut during operation of the crusher, and means operable to arrest rotation of said nut with the shaft whereby to adjust vertically in one direction said supporting portion and therewith the shaft as the result of relative shaft rotation.

2. In a gyratory crusher comprising an upright shaft, a rotary member in which one end of said shaft is eccentrically journalled and is slideable, a head fixed on said shaft and a fixed concave

surrounding the head, a nut rotatably supported at one end of said shaft, a supporting portion for the shaft threaded in said nut and rotating with the shaft and in turn normally rotating said nut during operation of the crusher, means operable to arrest rotation of said nut with the shaft whereby to adjust vertically in one direction said supporting portion and therewith the shaft as the result of relative shaft rotation, and means transmitting force from the gyratory motion of the shaft to the nut to rotate the same faster than the normal rotation of the shaft in the same direction as the shaft, whereby to adjust vertically in the other direction said supporting portion and shaft.

3. In a gyratory crusher comprising an upright shaft, a rotary member in which one end of said shaft is eccentrically journalled and is slideable, a head fixed on said shaft and a fixed concave surrounding the head, a nut rotatably supported at one end of said shaft, a supporting portion for the shaft threaded in said nut and rotating with the shaft and in turn normally rotating said nut during operation of the crusher, and a controllable drive to said nut derived from the gyratory motion of the shaft for driving the nut faster than the normally rotating shaft whereby to adjust vertically said supporting portion and shaft.

4. In a gyratory crusher comprising an upright shaft, a rotary member in which one end of said shaft is eccentrically journalled and is slideable, a head fixed on said shaft and a fixed concave surrounding the head, a nut rotatably supported at one end of said shaft for gyratory movement therewith, a supporting portion for the shaft threaded in said nut and rotating with the shaft and in turn normally rotating said nut during operation of the crusher, an externally toothed inner planetary gear fixed to said nut, an internally toothed outer orbit gear surrounding said inner gear and mounted for rotation on a fixed axis, said gears having a size and tooth ratio effecting simultaneous gyratory planetation of the inner gear within the outer gear while rotating the latter with the shaft, and means for arresting rotation of the outer gear, the ratio between the gears being such that when the outer gear is arrested, the speed and degree of rotation of the inner gear and nut are less than that of the shaft and said supporting portion so that the supporting member and said shaft will be displaced vertically in one direction due to relative shaft rotation.

5. Structure according to claim 4 wherein the gear ratio is 1 to 1.

6. Structure according to claim 1 wherein the nut is at the lower end of the shaft and wherein said supporting portion comprises a member beneath the shaft and coupled thereto by an Oldham coupling in a manner to permit relative tilting of the shaft.

7. Structure according to claim 1 wherein the nut is at the upper end of the shaft and wherein said supporting portion is the upper end of the shaft.

8. Structure according to claim 1 wherein means is provided to cause rotation of the nut in the same direction as the direction of normal shaft rotation and at a faster rate, to adjust in the other direction, the supporting portion and the shaft relative to the nut.

9. Structure according to claim 2 wherein the nut is at the lower end of the shaft and wherein said supporting portion comprises a member be-

neath the shaft and coupled thereto in a manner to permit relative tilting of the shaft.

10. In a gyratory crusher comprising an upright shaft, a rotary member in which one end of said shaft is eccentrically journalled and is slidale, a head fixed on said shaft and a fixed concave surrounding the head, a nut rotatably supported at one end of said shaft for gyratory movement therewith, a supporting portion for the shaft threaded in said nut and rotating with the shaft and in turn normally rotating said nut during operation of the crusher, an externally toothed inner planetary gear fixed to said nut for gyratory movement therewith, an internally toothed outer orbit gear surrounding said inner gear and mounted for rotation on a fixed axis, said gears having a size relation permitting gyratory planetation of said inner gear in engagement with said outer gear while rotating the same, and means operable to arrest said outer gear, the tooth ratio between the inner and outer gears being more than one to one, whereby when said outer gear is arrested, the gyratory planetation of said inner gear will cause said inner gear and nut to be driven in the direction of normal shaft rotation at a speed greater than that of the shaft so that said supporting portion and therewith said shaft will be displaced vertically in one direction.

11. Structure according to claim 10 wherein the nut is at the lower end of the shaft and wherein said supporting portion comprises a member beneath the shaft and coupled thereto in a manner to permit relative tilting of the shaft.

12. In a gyratory crusher comprising an upright shaft, a rotary member in which one end of said shaft is eccentrically journalled and is slidale, a head fixed on said shaft and a fixed concave surrounding the head, a nut rotatably supported at one end of said shaft for gyratory movement therewith, a supporting portion for the shaft threaded in said nut and rotating with the shaft and in turn normally rotating said nut during operation of the crusher, an externally toothed inner planetary gear fixed to said nut, an internally toothed outer orbit gear surrounding said inner gear and mounted for rotation on a fixed axis, said gears having a size and tooth ratio effecting simultaneous gyratory planetation of the inner gear in engagement with the outer gear while rotating the latter with the shaft, means operable to arrest the outer gear, the ratio between the gears being such that when the outer gear is arrested, the speed and degree of rotation of the inner gear and nut are less than that of the shaft and said supporting portion, so that the supporting member and said shaft will be displaced vertically in one direction due to relative shaft rotation, a second externally toothed inner planetary gear fixed to said nut for gyratory movement therewith, a second internally toothed outer orbit gear surrounding said second inner gear and mounted for rotation on a fixed axis, said second gears having a size relation permit-

ting gyratory planetation of said second inner gear in engagement with said second outer gear while rotating the same, and means operable to arrest rotation of said second outer gear, the tooth ratio between said second inner and outer gears being more than one to one, whereby, when said second outer gear is arrested, the gyratory planetation of said second inner gear will cause said second inner gear and nut to be driven in the direction of normal shaft rotation at a speed greater than that of the shaft so that said supporting portion and therewith said shaft will be displaced vertically in the opposite direction.

13. Structure according to claim 12 wherein the nut is at the lower end of the shaft and wherein said supporting portion comprises a member beneath the shaft and coupled thereto in a manner to permit relative tilting of the shaft.

14. In a gyratory crusher having a stationary lower frame, a member supported for rotation in said frame on a fixed vertical axis and having an upright cylindrical bore disposed on an axis which is eccentric with respect to and inclined from said vertical axis, said bore terminating in a bottom surface normal to its axis, an upwardly facing cup-like bearing unit supported coaxially in said bore by said bottom surface, and a crusher shaft having its lower end disposed coaxially within said unit and supported against downward movement exclusively by said unit.

15. A crusher in accordance with claim 14 characterized by the inclusion of antifriction bearing means between the bottom of said member and said unit.

16. Structure according to claim 14 wherein the cup-like bearing unit includes a bottom end wall forming element constituting the support for the shaft and wherein said element is vertically adjustable for vertical adjustment of the shaft.
